(57) CLAIM

The ornamental design for a bag, as shown and described.

DESCRIPTION

FIG. 1 is a top perspective view of a bag, showing my new design with a top flap in a closed position and bottom straps in a deployed position;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a top perspective view thereof, illustrated with the top flap in an open position;

FIG. 9 is a bottom perspective view of FIG. 2; and,

FIG. 10 is a bottom perspective view thereof, illustrated with the bottom straps in a stowed position.

The dashed broken lines showing a logo on the top flap medallion and on zipper pulls on the bag depict portions of the bag that form no part of the claimed design. The remaining dashed broken lines shown on the bag depict stitching, and are included in the claimed design. The dashed broken lines showing a human and rolled documents in FIG. 1 depict environment and form no part of the claimed design. The long dashed broken lines in FIGS. 1, 6, and 8, depict portions of the interior of the bag, which form no part of the claimed design.

1 Claim, 8 Drawing Sheets
